UNITED STATES PATENT OFFICE.

CLARENCE W. JAMESON, OF LOMBARD, ILLINOIS.

ELECTRIC SWITCH.

Application filed December 1, 1920. Serial No. 427,612.

To all whom it may concern:

Be it known that I, CLARENCE W. JAMESON, a citizen of the United States, residing at Lombard, in the county of Du Page and State of Illinois, have invented certain new and useful Improvements in Electric Switches, of which the following is a specification.

My invention relates to electrical switches, and more particularly to a motor-starting control-switch for automatically effecting the gradual cutting out of resistance from the line circuit in starting a motor.

Among the objects of my invention are to provide a controller switch employing a body or bodies of mercury as the shiftable circuit-opening-and-closing means in a construction that may be small in size, of low weight, low cost, and high efficiency. Other objects of the invention are to provide for accurate timing of the successive operations of cutting out resistance and to make the construction practically tamper-proof in this regard; to employ but a small number of moving parts and attain effectiveness and simplicity in the device.

In the drawings wherein I have illustrated a particular embodiment of my invention for purposes of disclosure, Fig. 1 is an elevation with parts in section, substantially on line 1—1 of Fig. 2; Fig. 2 is a cross-sectional elevation on line 2—2 of Fig. 1; Fig. 3 is a plan section of the movable switch-body showing a wiring diagram therefor, the switch-section being taken substantially on line 3—3 of Fig. 4; Fig. 4 is a section on line 4—4 of Fig. 3 showing the switch block in normal or open circuit position; and Fig. 5 is a similar view showing the same tilted to closed-circuit position.

In the drawings 10 indicates a suitable casing or housing for the assembled parts, having an insulating strip 11 along its front through which extend the binding posts 12 for the connection of external wiring with the casing-contained wiring. Mounted in the casing are a tiltable mercurial-switch structure 13, an actuating magnet 14 for controlling its tilting movements, and a series of resistance elements 15. The general arrangement is such that the resistance elements are normally in circuit and magnet 14 deenergized. When magnet 14 is energized the switch is rocked thereby

and sequentially, at proper intervals, shunts out the coils.

The resistance elements 15, to protect the motor in starting and thereafter be cut out of the motor circuit, are preferably long slender coils that, as shown, are mounted on shelves 16 extending lengthwise of the casing near the top thereof, so that these coils run transversely of the casing in spaced relation. Their windings are connected in series, as usual in rheostats, and the connections between them are provided with clips 17 for tap connections that run to the relatively-fixed contacts of the tiltable switch structure 13.

The switch structure 13 is preferably an oblong rectangular block internally chambered to hold mercury, and provided with relatively fixed contacts that extend into the mercury-receptive wells in the interior thereof. It is pivotally mounted so that by tilting the block pivotally from normal inclination to reverse inclination the mercury runs into coacting relation to the relatively fixed contacts. Specifically, the block 13 has a lug 18 mounted on its bottom and extending well below the center of gravity of the block, this lug being mounted on a longitudinal shaft 19 which finds bearing in the end walls of the casing. The block 13 may be rocked from the position shown in Fig. 4 to that shown in Fig. 5, that is to say from the position with its front edge elevated to a position with its rear edge elevated, by means of a lever 20 that is mounted on a stub-shaft 21 projecting from the end of the casing, this lever having one end portion slotted as at 22 for engagement with a stud 23 on the end of the block 13, and having a forked lever arm 24 engaged with a pin 25 that is carried by a prolongation of the stem or core 26 of the solenoid magnet 14, the magnet being mounted on a bracket 27 carried by the end wall of the casing.

It is preferred, in this general construction, that the weight of the movable parts is normally unbalanced, the preponderating weight of the switch block or element 13 being in rear of its pivotal axis 19 and the weight of the solenoid core tending to hold the switch normally in the position shown in Fig. 4. The tilting of the switch element to the position shown in Fig. 5 (and consequent shifting of the mercury within the

switch-body) does not overcome this weight-preponderance that tends to place the switch in the normal position above-stated, with its front edge elevated.

5 As specifically illustrated, the switch block comprises a rectangular body portion 28 of insulating material, provided with suitable recesses, forming chambers or wells for the reception of mercury and with passages for 10 mercury-flow. This body is overlaid by a removable packing-sealed cover 29, making an air-tight closure of the several mercury-chambers. As shown in Fig. 3 the fixed contact members A to J extend through the 15 front wall of the block, each having an external binding post portion 30 and an internal rounded "acorn-shaped" contact-stud portion 31, each stud being contained in a bay or different one of the wells 32. As 20 illustrated, the block is of construction to receive three separate bodies or masses of mercury M, these being respectively in the end mercury-chambers 34 and 35 and in the intervening main mercury chamber 36, (the 25 illustration of the mercury being omitted in some views for clarity). Preferably, further, each mercury-mass has floated on it a body of lighter, non-inflammable liquid, such as carbon-tetrachloride, that is a good 30 arc-suppressant, this body N substantially filling (save for a slight expansion-space) all the mercury-free space in the body. End chamber 34 opens directly and without restriction to the two wells or bays for the 35 end contacts A and B, and chamber 35 is in the same relation to the contacts I and J, so that when the device is tipped to Fig. 5 position the mercury body in each of these chambers will immediately flood both 40 appurtenant contact-wells, bridging the intervening barrier and establishing connection through the mercury between the respective pair of contacts that form a double-make-and-break line switch. Of course on restoration 45 to normal position the mercury flows out of the contact wells, the tetrachloride of carbon N floating up to fill them and suppress any arcing-tendency.

The main mercury chamber 36 is preferably of triangular shape, with its base toward the rear and its apex communicating through supply duct 38, with that well containing contact H. This channel is preferably valved for adjustment of the rate of 55 flow of mercury as by a screw 39 that is adjustable from the bottom of the block and that has its head covered by the metal base plate 40, to which block 28 is screwed, or by a sealing body 40' so that unauthorized 60 change of the timing adjustment is made unlikely. The screw 39 may work in a sleeve 39' through which a part of duct 38 is drilled, this sleeve being molded fast into the insulating block or body.

65 Each of the wells for the contact series H

to C communicates with the one next to it by a suitably-small port 42, so that no material quantity of mercury will flow into any well until all wells preceding it have been filled. Return flow passages 43 lead 70 back from the wells 32 to the base of triangular chamber 36. Thus, when the device, initially standing in rearwardly tilted position, with practically all of its main mercury body resident in main chamber 36 75 (as indicated by the mercury-level line in Fig. 4) is tilted to Fig. 5 position, the mercury flows at regulated rate through the valved supply duct 39, (only a very small quantity passing through passages 43) first 80 filling the well for terminal H, then overflowing through port 42 into the well for terminal G, and so on throughout the series until it fills all of the wells and connecting 85 passages for the contacts C to H.

As illustrated in Fig. 3 the construction described may appropriately be wired so that the motor supply line wires 50 and 51 are bridged by the high resistance solenoid 14 under the control of a hand switch 52. 90 Upon the closing of switch 52 the solenoid is energized and the mercurial switch is rocked to circuit closing position. One line wire has connection to contact A and the other line wire to contact J. The motor O is connected between the contacts B and C, and between the contacts C and I are arranged the series-connected resistance coils 15, with 95 taps 53 running from the several intervening contacts to connections between resistance coils, each contact that is sequentially brought into mercurial connection with its predecessor in the series cuts out one or more coils. As a matter of preference all taps from the coils are run to the binding 100 posts 12 on the front insulating block 11, flexible connections 54 being made therefrom to the proper contact binding posts 30 of the rocking switch member.

It will be observed that in the particular construction described and shown energization of magnet 14 will cause the line circuit to be closed promptly and simultaneously at the two terminal contact pairs A-B and I-J, and on deenergization of magnet 14 110 the line-circuit break will also be double, thus insuring a rapid and effective make-and-break action with minimum tendency to arcing and with the break occurring in an air-tight chamber preferably nearly filled 115 with inert liquid. With respect to the resistance-controlling contacts of the central group, these are caused to cut out the resistance elements sequentially at a time interval that may be very nicely regulated and 120 that, once set, will be very accurately maintained.

While I have herein described a specific embodiment of my invention that I have found to be practical and efficacious, for 125 130

purposes of full disclosure thereof, it will be understood by those skilled in the art that many changes in detail might be made without departure from the spirit of my invention within the scope of the appended claims.

I claim:

1. In a motor-starting switch, a switch element mounted to rock to raise either side-edge above the other and comprising a body having therein a main mercury chamber having an apex toward one side edge of the body and its base toward the opposite edge, a plurality of wells sequentially connected disposed along said first edge and the first thereof respectively connected with the apex of said main mercury chamber, the connections between said wells being arranged to prevent the flow of mercury into one well until all of the preceding wells have been filled, respective return passages from the several wells to the base of said main chamber, contacts in said wells, and a body of mercury, normally resident in said main chamber, adapted to flow into and fill the connected wells when the switch element is rocked thereby to bring the said contacts successively into common connection.

2. A motor-starting switch comprising a body having a chamber, said body having a plurality of wells sequentially connected, the first of said wells being connected with said chamber, a plurality of contacts each located in one of said wells, a quantity of mercury located normally in said chamber and adapted to enter said wells in succession upon movement of said body to connect said contacts, the connections between said wells being arranged to prevent the flow of mercury into one well until all of the preceding wells have been filled, and means for effecting a movement of said body to cause the flow of mercury into said wells.

3. A motor-starting switch comprising a body having a chamber, said body being provided with a series of connected wells, the first of said wells being in communication with said chamber, a series of contacts each located in one of said wells, a quantity of mercury located normally in said chamber, a series of individual return passages each leading from one of said wells to said chamber, and means for tilting said body to cause said mercury to fill said wells and connect said contacts, and to effect a reverse tilting whereby said mercury flows back to said chamber through said return passages.

4. A motor-starting switch comprising a body having a chamber, said body having a plurality of wells sequentially connected, the connections between said wells being arranged to prevent the flow of mercury into one well until all of the preceding wells have been filled, a regulable passage from said chamber to the first of said wells, a

plurality of contacts each respectively located in one of said wells, a quantity of mercury located normally in said chamber and adapted to enter said wells in succession upon movement of said body, thereby to connect said contacts, and means for effecting a movement of said body to cause the flow of mercury into said wells.

5. In a motor-starting switch-structure, a tiltable switch element comprising a body having therein a series of sequentially connected wells, a main mercury chamber having an apex toward said wells, a supply passage from said apex of said chamber to the first of said wells, and return passages from the other wells to the base of the mercury chamber, contacts in said wells; a second, separate mercury chamber having wells directly open thereto, contacts in said wells and mercury bodies in said chambers to flow into and out of contact-connecting position according to the tilt of the element.

6. In a motor-starting switch-structure, a tiltable switch element comprising a body having therein a series of sequentially connected wells, a main mercury chamber having an apex toward said wells, a supply passage from said apex of said chamber to the first of said wells, and return passages from the other wells to the base of the mercury chamber, contacts in said wells; a plurality of other, separate mercury chambers each having wells directly open thereto, contacts in said wells and mercury bodies in said chambers to flow into and out of contact-connecting position according to the tilt of the element.

7. A tiltable switch structure comprising an insulating body and cover forming an elongated block, a pivotal support therefor having a longitudinal pivotal axis, said body having therein near one longitudinal edge a series of wells and having a main mercury chamber tapering to an apex and with its base toward the opposite edge, a communication passage transversely of the body from the apex of said chamber to the first well, longitudinal communication ducts between the portions of the several wells remote from the block-edge arranged to permit mercury flow to any well only after all preceding wells have been filled, and respective transverse return passages from said wells to the base of the main chamber; contacts in the wells and a mercury body normally resident in said main chamber adapted to fill the wells when the structure is tilted.

8. A tiltable switch structure comprising an insulating body and cover forming an elongated block, a base for the block, a pivoted support therefor having a longitudinal pivoted axis, said body having therein near one edge a series of wells and having a main mercury chamber tapering to an apex and with its base toward the other edge, a com-

munication passage transversely of the body from the apex of said chamber to one well, a screw-valve for regulating said passage having its head covered by said base, longitudinal communication ducts between the portions of the several wells remote from the block-edge, and transverse return pas-

sages from said wells to the base of the main chamber; contacts in the wells and a mercury body normally resident in said main chamber adapted to fill the wells when the structure is tilted. ¹⁰

CLARENCE W. JAMESON.
